(57) **CLAIM**

The ornamental design for a baking mold, as shown and described.

DESCRIPTION

FIG. 1 is a top, front, left side perspective view of a first embodiment of the baking mold of the new design.

FIG. 2 is a front elevation view of the baking mold of FIG. 1, the rear, left side, and right side elevation views being identical as the device is rotationally symmetric.

FIG. 3 is a top plan view thereof.

FIG. 4 is a bottom plan view thereof.

FIG. 5 is an exploded perspective view thereof.

FIG. 6 is a cross-sectional view taken along line 6-6 of FIG. 2 at an enlarged scale.

FIG. 7 is an exploded perspective view of a second embodiment of the baking mold of the new design.

FIG. 8 is a cross-sectional view of the baking mold of FIG. 7.

FIG. 9 is an exploded perspective view of a third embodiment of the baking mold of the new design; and,

FIG. 10 is a cross-sectional view of the baking mold of FIG. 9.

The broken lines in the drawings depict portions of the baking mold that form no part of the claimed design.
